Inventor

LeRoy L. Thompson

UNITED STATES PATENT OFFICE.

LEROY L. THOMPSON, OF HAVERHILL, ASSIGNOR TO ARTHUR L. ADAMS, OF LEXINGTON, MASSACHUSETTS.

DESIGN FOR AN INK-ERASER.

SPECIFICATION forming part of Design No. 19,440, dated November 19, 1889.

Application filed September 24, 1889. Serial No. 324,880. Term of patent 7 years.

To all whom it may concern:

Be it known that I, LEROY L. THOMPSON, a citizen of the United States, residing at Haverhill, in the county of Essex and State of Massachusetts, have invented a new and useful Ink-Eraser, of which the following is a specification, reference being had to the accompanying drawing, forming part of this specification, in which the single figure is a perspective view representing the design, this single view being deemed necessary to fully illustrate my design.

The leading feature of my design consists in a cylindrical-shaped handle having at each end the spoon-shaped blades set at opposing angles. These blades, while spoon-shaped in outline, are flat in cross-section.

A is the handle of the eraser, which is cylindrical in its general outline, with a slight swell or enlargement in the center of the handle and tapering toward each end. On the ends of the handles are placed tubular ferrules B.

C C' are blades made substantially spoon-shaped in outline and inserted in the ends of the handles. The blade C has its under side provided with a roughened or file surface, while the blade C' has its under side entirely smooth.

Both blades are set at an angle of about forty-five degrees; but the angle of inclination of the blades oppose each other—that is to say, the 30 blade C points to one side of the handle, while the blade C' extends to the other side of the handle. The combined arrangement of the two blades pointing in opposite directions, with the oppositely-tapering cylindrical shape 35 of the handle, presents to the eye a novel and pleasing design.

What I claim is—

The design for an eraser herein shown and described, the same comprising an oppositely-tapering cylindrical-shaped handle A, and the blades C C', extending in opposite directions from the ends of the handle, the said blades being substantially spoon-shaped in outline and the blade C having its under side 45 provided with a file or roughened surface.

In testimony that I claim the foregoing as my own I have hereto affixed my signature in presence of two witnesses.

LEROY L. THOMPSON.
